US0D1099445S

(12) **United States Design Patent** (10) **Patent No.:** **US D1,099,445 S**
(45) **Date of Patent:** **** Oct. 21, 2025**

(54) **DOG TRAINING DEVICE SET**

(71) Applicant: **Shenzhen Diai Intelligence Technology Co., Ltd**, Shenzhen (CN)

(72) Inventor: **Shaojia Yu**, Guangdong (CN)

(**) Term: **15 Years**

(21) Appl. No.: **29/954,395**

(22) Filed: **Jul. 26, 2024**

(51) LOC (15) Cl. **30-99**

(52) U.S. Cl.

USPC **D30/199; D10/104.1**

(58) **Field of Classification Search**

USPC ..... D30/151–155, 144, 199, 160, 119/792–798, 850, 855–859, 863–865, 119/654, 905, 907, 815, 712, 802, 784, 119/769, 760, 776, 862, 908, 860, 119/719–721; 242/381.1–381.2, 385.4, 242/378.3, 376.1, 385.1, 916, 601, 570, 242/405, 404, 371, 223, 170, 388.1, 242/405.2, 377, 381.3, 381.6, 405.3, 242/388.6, 384.7, 382, 396.1, 404.1, 380; 362/108; 33/767, 769, 414; D12/400; D3/229, 230, 207, 208, 215; 40/1.5, 455, 40/640, 303; 206/63.3, 459.5, 702, 408; D6/515; D8/358, 360, 347, 360.1, 359, D8/356, DIG. 1; D24/145, 167, 186, 146, D24/169; D10/57, 72, 106.1, 104.1, D10/104.2, 109.2, 70, 97, 98, 78, 65; D20/28; 224/666, 678; 16/445; 283/74, 283/70; D11/232, 200, 216, 1, 2, 86, 87, D11/201, 206–210, 212–215, 218; 24/163 K, 122.3, 323, 702, 600.4–600.7, 24/163 R, 169–171, 173, 177–179, 191, 24/194, 195, 197, 200, 303, 616, 635, 24/313, 615, 3, 6, 3 K, 599.2, 96, 221, 24/237, 311, 312, 314, 321, 338, 339, 24/309; 428/3, 4; 54/76, 1, 71; 63/29.1, 63/3; 191/12.2 R, 12.4; D13/154, 153, D13/137.4, 155, 103, 168; D19/69, 67;

CLAIM

The ornamental design for a dog training device set, as shown and described.

DESCRIPTION

FIG. 1 is a perspective view of a dog training device set showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, bottom perspective view thereof.

FIG. 9 is an enlarged detail view of area 9 shown in FIG. 1; and,

FIG. 10 is an enlarged detail view of area 10 shown in FIG. 8.

The broken lines in the drawings depict portions of the dog training device set that form no part of the claimed design.

1 Claim, 10 Drawing Sheets
